UNITED STATES PATENT OFFICE.

MARTIN GOEHRING, OF YOLYN, WEST VIRGINIA.

WRENCH.

1,088,413.

Specification of Letters Patent.

Patented Feb. 24, 1914.

Application filed September 17, 1913. Serial No. 790,267.

To all whom it may concern:

Be it known that I, MARTIN GOEHRING, a subject of the German Emperor, residing at Yolyn, in the county of Logan and State of West Virginia, have invented certain new and useful Improvements in Wrenches, of which the following is a specification, reference being had to the accompanying drawings.

10 This invention relates to new and useful improvements in wrenches and more particularly to a quick adjustable wrench, and the primary object of the invention is to provide a device of this character which may 15 be quickly and readily adjusted to the desired position without removing the wrench from position on the object to be turned.

A further object of the invention resides in providing a wrench having a handle of 20 sigmoidal design whereby to permit the head of the wrench to be introduced in places in positions that will not admit of wrenches of the ordinary type to be introduced.

A still further object resides in providing 25 a device which is simple and durable in construction, inexpensive to manufacture, and which will be very efficient and durable in operation.

With these and other objects in view, my 30 invention consists in the novel features of construction, combination and arrangement of parts as will be hereinafter referred to and more particularly pointed out in the specification and claim.

35 In the accompanying drawings forming part of this application, Figure 1 is a plan view of my device. Fig. 2 is a side elevation thereof, with parts in section. Fig. 3 is a vertical longitudinal section through the device, with parts removed. Fig. 4 is a transverse section through the head of the wrench showing the ratchet and pawl connection and the spring arrangement between the movable jaw and the housing. Fig. 5 is a 40 top plan view of the device with parts broken away. Fig. 6 is an elevation of the movable jaw showing the ratchet teeth on the shank thereof. Fig. 7 is a vertical section through the movable jaw. Fig. 8 is a 45 side elevation of the movable jaw with the shank thereon, and Fig. 9 is a vertical longitudinal section through the head of the wrench.

In describing the invention, I shall refer 50 to the drawing in which similar reference

characters designate corresponding parts throughout the several views and in which—

1 indicates a shank of sigmoidal design, the one end thereof having a housing 2 formed thereon and a stationary jaw 3 is 60 formed at the one end of said housing to project substantially at right angles to the general turn of the housing. The housing has a channel-way extending completely therethrough which also extends below the 65 stationary jaw, and the one wall of this channel-way, that is, the inner face of one wall of the housing, is provided with a longitudinal rib 4. The channel-way formed in the housing is disposed in a plane sub- 70 stantially at right angles to the plane of the contacting face of the stationary jaw 3 and sildably mounted in said channel-way is a shank 5 which has a jaw 6 formed on the outer end thereof, said jaw being termed a 75 movable jaw. The one side of this shank is provided with a groove 7 to receive therein the longitudinal rib 4 on the one wall of the housing, and the jaw 6 at the outer end of the shank 5 is disposed in a plane at sub- 80 stantially right angles to the plane of the shank to co-act with the stationary jaw 3.

Formed on the outer face of the wall of the housing opposite that having the rib 4 thereon, are a pair of ears 8 between which 85 is pivoted a dog or the like 9, said dog having its effective end engaged in the ears thereof projecting through an opening 10 in the adjacent wall of the housing. One side of this shank 5 is provided for a portion of 90 its length with teeth 11 with which the effective end of said dog is adapted to be engaged and the outer end of said dog is designed to form a finger piece, as shown at 12. A spring engaged with the end face of 95 said finger piece and with the shank 1 acts on said dog so as to dispose the same normally to its effective position in engagement with the teeth of the shank 5, thereby retaining the movable jaw 6 in its adjusted position and in order to move said shank 5 to 100 correspond with the jaw 6 thereof, it is necessary to release the engagement of the dog with the teeth 11 by forcing downwardly on the finger piece against the tension of the 105 spring 13.

The shank 5 from its inner end is provided with a channel 14 which is substantially of circular design in cross section and extends for a greater portion of the length of said 110

shank, and the side of said shank having the teeth 11 therein is slotted longitudinally, as shown at 15, to communicate with said channel. Arranged in said channel 14 is a coil 5 spring 16, and a pin or projection 17 carried on the one wall of the housing and extending inwardly, is received through the slot 15 and channel 14 of the shank 5. The projection 17 engaging the coil spring 16 in the 10 channel 14 compresses said coil spring and when said shank and jaw 5 and 6, respectively, are retained in any adjusted position, the same are held in such position against the tension of said coil spring 16. As long, 15 therefore, as the dog is released from its engagement with the teeth 11 of the shank, it will be seen that said shank and jaw 5 and 6 respectively, will be forced outwardly under tension of said spring 16. Through this medium all adjustments of the wrench will be 20 quickly and readily made.

From the foregoing description of the construction of my improved device, the operation thereof will be readily understood and 25 it will be seen that I have provided a quick acting wrench which is simple and durable in construction, inexpensive to manufacture, and one which is very efficient and useful in operation.

30 While I have particularly described the elements best adapted to perform the functions set forth, it is obvious that various changes in form, proportion and in the minor details of construction may be resorted to, 35 within the scope of the appended claim, without departing from the spirit or sacrificing any of the principles of the invention.

Having thus described my invention, what 40 I claim, is:

A wrench of the class described including a shank, a housing formed on one end there-

of having a longitudinal channel extending completely therethrough, a stationary jaw formed on one end of said housing and having its engaging face arranged in a plane at 45 right angles to the plane of the upper edge of said housing, one wall of said housing having an opening therein, a longitudinal rib on the inner face of said wall, an additional shank arranged for sliding movement 50 in said housing and having a longitudinal groove to receive the aforesaid longitudinal rib, an additional jaw formed on one end of the additional shank and having its engaging face arranged in a plane at right angles 55 to the upper face of said last mentioned shank, said last mentioned jaw forming a movable jaw for coöperation with the stationary jaw, said additional shank having a longitudinal channel therein terminating in 60 a slot in one side of said shank, a coil spring arranged in the channel, an inwardly extending projection on the wall of said housing disposed through the slot and channel and adapted for engagement with one end 65 of said coil spring, to compress the latter when the movable jaw is forced inwardly toward the stationary jaw, a series of teeth formed on one side of the movable shank and a spring pressed pivoted dog carried on 70 the housing and having its effective end disposed through the opening in the first mentioned shank to engage said teeth and retain the movable shank and jaw in any desirable position. 75

In testimony whereof I hereunto affix my signature in the presence of two witnesses.

MARTIN GOEHRING.
